TOY AUTOMOBILE

Thomas Janosko, 5149 Miller Ave., Maple Heights, Ohio

Filed July 21, 1960, Ser. No. 61,481

Term of patent 7 years

(Cl. D34—15)

FIGURE 1 is a perspective view, taken from above, of a toy automobile showing my new design, showing the wheels aimed straight ahead and the eye balls normally positioned;

FIGURE 2 is a perspective view, with the wheels turned to the extreme left, showing the left eye ball protruding and the right eye ball retracted;

FIGURE 3 is a perspective view, with the wheels turned to the extreme right, showing the right eye ball protruding and the left eye ball retracted;

FIGURE 4 is a front elevation of the toy automobile, and

FIGURE 5 is a rear elevation.

The appearance of the left side of the body is the same as that of the right side.

I claim:

The ornamental design for a toy automobile, as shown and described.
